United States Patent Office

Des. 176,593
Patented Jan. 10, 1956

176,593

MEDALLION

Robert J. Carlyle, Brooklyn, N. Y.

Application May 12, 1955, Serial No. 35,946

Term of patent 3½ years

(Cl. D29—2)

FIG. 1

FIG. 2

Fig. 1 is a front elevational view of a medallion, showing my new design; and

Fig. 2 is a side elevational view thereof, looking from the left of Fig. 1.

The rear of the medallion is smooth.

I claim:

The ornamental design for a medallion, as shown and described.
